ROLLER SIDE BEARING

Henry F. Wardwell and Walter C. Bladin, Chicago, Ill., assignors to W. & B. Company, Chicago, Ill., a corporation of Illinois

Application December 18, 1930
Serial No. 503,179

8 Claims. (Cl. 308—226)

This invention relates in general to roller bearings, and more particularly to roller side bearings for the trucks of railway cars.

The principal objects and advantages which 5 reside in the present invention are the provision of an improved roller side bearing and housing formed in separate parts and a roller wherein said housing is provided with means for retaining the roller against accidental dislodgment; 10 the provision of an improved side roller bearing for railway cars wherein the roller has a limited area of contact at the ends of its rolling movement to prevent freezing or jamming of the roller; the provision of an improved housing for 15 the roller which includes a separable base provided with means for reinforcing the side walls of the housing; the provision of a bearing of the type referred to, wherein the several parts of 20 the housing, including the base and side and end walls, are secured in position on a truck bolster by common securing means arranged conveniently 25 within the outlines of the housing; the provision of an improved housing for side roller bearings in which provision is made for the 30 drainage of moisture continuously from the housing and thus preventing an accumulation and freezing therein of water of condensation; and the provision of a bearing of the character referred to which is strong, substantial and economical to manufacture and convenient to install in operative position.

The foregoing and such other objects and advantages as may appear or be pointed out as this 35 description proceeds are attained in the structural embodiment illustrated in the accompanying drawing, in which:

Figure 1 is a top plan view of the bearing, including the improvements, of this invention;

Figure 2 is a side elevational view of the same;

Figure 3 is a longitudinal view, taken on the line 3—3 of Figure 1 looking in the direction indicated by the arrows;

Figure 4 is an end elevational view; and

Figure 5 is a transverse vertical sectional view, parts being broken away, taken on the line 5—5 of Figure 1 looking in the direction indicated by the arrows.

Referring now more particularly to the drawing, the device of this invention includes a hous-

ing H and a roller R which form the major portions of the bearing.

The housing H comprises the base portion B which is preferably a casting as is the upper portion of the housing. The base portion B is provided with a raised intermediate portion 5 formed with a runway comprising the oppositely inclined surfaces 6 and 7 which terminate in the center of the runway and form shoulders 8 and 9 at the outer ends of the runway. These inclined 55 surfaces 6 and 7 terminate along their longitudinal margins spaced from the side walls 10 and 11 of the housing to afford drain grooves 12 and 13. At the medial portion of the runway the casting B is provided with a reinforcing foot 60 portion 14 which receives the thrust of the roller R when at the bottom of the runway.

The base is extended longitudinally beyond the shoulders 8 and 9 to form base lugs 15 and 16 which are apertured, as at 17 and 18, to provide 70 fastening means by bolts or rivets not shown.

The base B at its medial portion on either side is provided with laterally extending portions 19 and 20 formed with upstanding lugs 21 and 22 which are spaced from the adjacent longitudinal 75 edges of the casting to afford grooves for receiving the lower edges of the side walls 10 and 11. Thus the lugs 21 and 22 form reinforcing means for the side walls at these points.

The upper portion of the housing, indicated as H, includes preferably a casting having the side walls 10 and 11 and cylindrical end walls 23 and 24, said end walls 23 and 24 joining the side walls 10 and 11 in such manner that end limit stop abutments 25, 25 and 26, 26 are afforded 85 against which the peripheral bearing surface 27 of the roller R is adapted to abut. Thus, when the roller reaches either of its limits of longitudinal movement in the housing, the peripheral surface of the roller contacts with the abutments 25 or 26 with a relatively limited area of contact so that the possibility of the roller freezing, due to the accumulation of water at these points, is substantially eliminated. It will be understood that often a freight car is left standing on a 90 curved track for some time, and that the possibility of the roller freezing in position and destroying its functioning under these conditions is 95 eliminated in the present invention.

The side walls 10 and 11 at their medial por- 100

tions along their lower edges are provided with notches 29 and 30 which engage the lateral projections 19 and 20 and thus these projections serve to prevent relative longitudinal movement of the housing and base. To further prevent such movement, the end lugs 15 and 16 are extended outwardly so as to conform to the shape of the end walls and side walls, as indicated at 31 and 32 in Figures 2 and 4, so that said lugs underlie 10 the end and side walls at these points, and, additionally, afford abutments 33 and 34 for preventing relative longitudinal movement of the casting H on the base B.

For securing the casting H in position and also 15 the base B, the casting H is provided with integral transverse foot portions 35 and 36 which overlie the lugs 15 and 16 and are apertured, as at 37 and 38, complementally to said apertures 17 and 18, the fastening means being extended 20 through said apertures to form a common retaining means. The inner edges of the foot portions 35 and 36 abut the shoulders 8 and 9. It will thus be understood that the projections 19 and 20, shoulders 33 and 34, and the foot portions 25 35 and 36 abutting the shoulders 8 and 9 serve adequately to prevent longitudinal displacement of the parts H and B. In addition, the lugs 21 and 22 prevent bulging of the side walls 10 and 11.

30 The upper margins of the side walls 10 and 11 and the cylindrical end walls 23 and 24 are provided with continuous external flanges 39 and 40, and the side walls 10 and 11 are, in addition, provided with inwardly directed reinforcing flanges 41 and 42 which serve to overlie the trunnions 43 and 44 of the roller R and prevent the latter from jumping out of the housing when in operative position.

40 Drain openings are provided at the ends of the housing by removing portions of the cylindrical walls 23 and 24 in forming the casting H, as indicated at 45 and 46, so that drainage of the housing is afforded at all times.

45 From the foregoing it will be understood that, in the provision of the housing having separable parts, in the event that the upper casting H becomes fractured or otherwise damaged in use, this may be readily removed and a new upper casting substituted. The housings and base portions are interchangeable and permit of the renewal of the housing without the necessity of renewing the base portion, which makes for economy in maintenance.

50 The housing serves, as pointed out above, to retain the roller member in position and to reduce the surfaces of contact between the ball and the retaining housing to a relatively small area, thus facilitating the free movement of the roller in the housing, and preventing the accumulation 55 of foreign matter or liquid which would tend to reduce the efficiency of the device in operation.

Having thus described our invention and illustrated its use, what we claim as new and desire to secure by Letters Patent is:

60 1. A side bearing for railway cars including an elongated housing of substantially rectangular horizontal cross-section having separate base member and side wall member and adapted to receive a roller, said side wall member having semi-cylindrical end walls forming abutments for limiting the movement of said roller, said end walls being provided with apertured horizontal base portions overlying complementally apertured portions of said base member, and adapted to receive common retaining means, said base member

and side wall member having integral co-operating means to prevent relative horizontal displacement independently of said common retaining means.

65 2. A side bearing for railway cars including an elongated housing of substantially rectangular horizontal cross-section having separate base member provided with a raised roller runway and a side wall member, the latter having end walls provided with apertured horizontal base portions overlying complementally apertured portions of said base member, and adapted to receive common retaining means, said base portions snugly abutting the ends of said raised roller runway for preventing relative longitudinal movement of the said base and side wall members.

70 3. In a device of the character described, in combination, a housing including a separable bottom member having extended end portions, a side-wall member having transverse base sections seated upon said extended end portions, and a raised roller runway on said bottom member, said base sections of said side-wall member fixedly abutting the end surfaces of said runway.

75 4. In a device of the character described, in combination, a housing including a separable bottom member with a raised roller runway terminating short of the ends thereof, a side wall member having transverse end portions seated on said bottom member and fixedly abutting against the ends of said raised roller runway, and said roller runway being formed with its ends relatively higher than its center, thus forming a roller pocket.

80 5. In a device of the character described, in combination, a housing including a separable bottom member with a raised roller runway terminating short of the ends thereof, a side wall member having transverse end portions seated on said bottom member, a raised roller runway on said bottom member terminating short of the ends thereof, the ends and side surfaces of said raised runway being in substantially snug contact with the under sides of the transverse end sections, and the side walls, respectively, of said side wall member, thus preventing horizontal displacement of said bottom member and said side-wall member with respect to each other.

85 6. In a device of the character described, in combination, a housing including a base member and a side-wall member superposed thereon, said base member having a raised roller runway, the sides and ends of which are in substantially snug contact with the inner vertical surfaces of said side wall member, the ends of said roller runway being relatively higher than its center, and grooves formed in the surfaces of said raised roller runway adjacent to said side walls, providing drainage from the center of said runway to the ends thereof.

90 7. In a device of the character described, in combination, a housing including a separable bottom member having extended end portions, a side wall member having transverse base members superposed on said end portions of said base member, a raised roller runway on said base portion having its end and side surfaces in vertical contact with said side wall member, said bottom member having laterally extending integral elements on the sides thereof, so formed to interlock with the side wall member as to prevent both longitudinal and transverse displacement of said side wall member relative to said bottom member, and to provide lateral support for said side wall member against lateral thrust.

8. In a device of the character described, in combination, a housing including a separable bottom member and a superposed side wall member, said bottom member and side wall member having integral interlocking portions which prevent relative horizontal displacement, a raised roller runway on said bottom member, said runway being relatively higher at its ends than at its center, the end walls of said side wall member being semi-cylindrical in horizontal cross-section, the diameter of said semi-cylindrical section being less than the clear distance between side walls, thus affording end chambers and vertical abutments in said housing, drain ports in said end walls, and a cylindrical roller member mounted upon said roller runway and limited in the travel by said vertical abutment. 80
